(57) **CLAIM**

The ornamental design for a light fixture, as shown and described.

DESCRIPTION

This application is related to commonly owned U.S. design patent application Ser. No. 29/197,499, filed Jan. 15, 2004.

FIG. 1 is a perspective view of the light fixture of the present design;

FIG. 2 is a front elevation view thereof;

FIG. 3 is a side elevation view thereof; the other side being a mirror image thereof;

FIG. 4 is a back elevational view thereof;

FIG. 5 is a top plan view thereof; and,

FIG. 6 is a bottom plan view thereof.

The broken lines shown are for illustrative purposes only and form no part of the claimed design.
